GAME APPARATUS

Speros P. Andelenis, Concord, N. H.

Application April 6, 1938, Serial No. 200,524

1 Claim. (Cl. 273—106)

The invention relates to a game apparatus and more especially to a disk throwing game apparatus.

The primary object of the invention is the pro-

5 vision of an apparatus of this character, wherein skill is required in the handling of disks for scoring purposes and such handling assures exercise during the playing of the game by the participants.

10 Another object of the invention is the provision of an apparatus of this character, wherein the disks designed to be thrown at a target are of novel construction so that a player may handle such disks in a convenient manner and for 15 obtaining a high score for the winning of a game.

A further object of the invention is the provision of an apparatus of this character, which is simple in its construction, entertaining in the 20 playing of a game, assuring exercise to a player and inexpensive to manufacture.

With these and other objects in view, the invention consists in the features of construction, combination and arrangement of parts as will be hereinafter more fully described, illustrated in 25 the accompanying drawing, which discloses the preferred embodiment of the invention and pointed out in the claim hereunto appended.

In the accompanying drawing:

Figure 1 is a perspective view illustrative of 30 the game apparatus constructed in accordance with the invention.

Figure 2 is an enlarged top plan view of one of the throwing disks or playing pieces of the apparatus.

35 Figure 3 is a vertical sectional view throughout.

Similar reference characters indicate corresponding parts throughout the several views in the drawing.

40 Referring to the drawing in detail, the apparatus comprises a playing alley 10, being laid out on any permanent flat floor surface and in this instance is closed at opposite longer sides and one end by a fencing 11 or a guard planking, 45 while the other end remote from the closed end beingp ermanently opened. Close to the closed end of the alley 10 an upon its flat bed is created a target 12, in this instance in the form of a circle and a five-pointed star, the latter

50 being within the circle and through demarcations is divided while the points of the star divide the circle into scoring spaces 13 and 14, respectively, bearing indicia identifying scoring points or areas.

55 The fencing 11 at one longer side of the alley 10 has built therewith a return chute or trough 15 extending from the closed end to the open end

of said alley and this chute or trough at the open end communicates with a depository 16 for the reception of returned play pieces hereinafter described.

Each play piece is in the form of a disk-like body 17 having at one side thereof and following the outer peripheral edge an annular beveled area 18 while in the opposite face of said body 17 at its center is a circular depression or recess 19, being any number of play pieces for the playing a game by the apparatus according to rules and regulations in the playing of such game. This recess 19 in the body 17 constitutes a pocket for the fingers of the hand or hands of a player of a game when grasping the body 17 so that the latter can be thrown or tossed by such player when standing at the open end of the alley in the direction of the target 12 for effecting a scoring by the said playing piece coming to rest at the target and within one of the scoring spaces 13 20 or 14 thereof. The thrown play piece, after a scoring had thereby, will be returned in the chute or trough to the depository 16 to be acquired by a player for a throw thereof in the playing of a game.

25 A player acquiring the highest score through the throws of the play pieces becomes the winner of the game.

The play pieces are of a determined weight and in the use or throwing of the same give 30 exercise to a player when playing a game through such use. The play pieces are thrown in the alley 10 from the open end to the closed end thereof, being aimed at the target 12 and such pieces may be thrown high or caused to ski 35 the bed of such alley and scoring at the target 12 is had when such thrown play piece comes to rest thereon.

The beveled area 18 assists the proper grasp of 40 the play piece or body 17 in the hand of a player and coaction of this area with the pocket 19 for the fingers of the hand enables skillful throwing of the play piece for high scoring purposes in the playing of the game.

45 What is claimed is:

A game piece for playing a game comprising a disk-like body having at one side thereof and following the outer peripheral edge an annular beveled area and also in the opposite face of said body a center circular depression constituting a counterseated socket having a straight annular wall merging with the face next thereto and at right angles presenting a continuous ledge shoulder for the engagement of fingers of a hand of a player when grasping the body so that it 50 can be thrown or tossed by such player.

55 SPEROS P. ANDELENIS.
